INVENTOR

Roland W. Sellew
BY
Milchee Binders
ATTORNEY.

UNITED STATES PATENT OFFICE.

ROLAND WINCHESTER SELLEW, OF MIDDLETOWN, CONNECTICUT.

BINDER.

Application filed December 20, 1922. Serial No. 607,964.

To all whom it may concern:

Be it known that I, ROLAND W. SELLEW, a citizen of the United States of America, residing at Middletown, Connecticut, have ⁵ invented a new and useful Binder, of which the following is a specification.

My invention relates to a binder and is particularly adapted for permanently binding a book or plurality of sheets, and temporarily binding other sheets or a book in so called loose leaf fashion, all within the same cover.

It is the principal object of my invention to provide a binder in which a plurality of sheets may be permanently bound or secured, and in which other sheets may be temporarily held in so called loose leaf fashion. Other minor objects will be apparent as the specification proceeds.

²⁰ In the preferred form of my invention there is provided a binder member in which a book or plurality of sheets may be permanently secured. One or more rods or rings are likewise associated with the binder member and are adapted to pass through perforations in sheets. These rods or rings are adapted to be moved to open or closed positions for the purpose of inserting or removing sheets as is now commonly done with ²⁵ loose leaf binders. The permanently bound sheets and the temporarily bound sheets are preferably separated from each other at points adjacent the securing points.

³⁰ In the drawings, I have shown for illustrative purposes only, preferred forms of my invention. In said drawings:

Fig. 1 is a sectional view of a binder embodying features of my invention and illustrated in the open position.

⁴⁰ Fig. 2 is a view similar to Fig. 1 but showing the binder in closed position.

Fig. 3 is a view in front elevation of the binder shown in Fig. 2.

Fig. 4 is a sectional view illustrating a ⁴⁵ slightly modified form, the parts being shown in closed position.

Fig. 5 is a sectional view illustrating a further modification.

⁵⁰ Fig. 6 is a view of a detail and further modification.

Fig. 7 is a sectional view of a still further modified form.

In the forms illustrated in Figs. 1 to 4, 1 indicates a spring or resilient backing

plate or outer binder member. The side ⁵⁵ edges of the plate 1 are rounded as indicated at 2-2, so as to form pockets for receiving the free ends of the hinge members 3-4. These hinge members have ears ⁶⁰ 5-6 projecting from the sides thereof at their adjacent edges so as to cause the inner edges of the members 3-4 to remain in engagement with each other when in the positions indicated in Figs. 2 and 4. These ears likewise cause the adjacent edges of the members 3-4 to remain in engagement when in the open position as shown in Fig. 1 and it is only when the hinge members are opened up to a substantially greater extent than shown in Fig. 1 that the plates ⁶⁵ 3-4 ⁷⁰ will become disengaged. The overall length of the hinge is greater than the normal distance between the pockets in the plate 1, so that when the hinge is in the position indicated in Fig. 1, it may be forced inwardly and in this movement will stress the resilient backing plate 1 so that when the hinge is in closed position indicated in Fig. 2, the same will be thus held by the resilient or spring plate 1. ⁷⁵ ⁸⁰

Secured to the hinge member 3, in any suitable manner, such as by welding or riveting, is a channel member 7. Passing through the legs of the channel is a rod 8, forming part of a binder ring 9. The channel 7 and rod 8 are for the purpose of permanently securing a book or plurality of sheets to the binder and to that end the rod 8 is riveted or otherwise permanently secured to the channel after the book or sheets ⁸⁵ ⁹⁰ have been inserted in the channel. A complementary binder ring 10 is secured to the other hinge member 4, and co-acts with the ring part 9 for detachably holding sheets in the binder. It should be here noted that the ⁹⁵ number and arrangement of the binder rings and the length and arrangement of the channel are largely matters of choice and expediency.

In the form shown in Fig. 4, channels 11, ¹⁰⁰ 12 are secured to each of the hinge members 3-4, and the two binder ring parts 13, 14 co-operate with their respective channels for permanently securing two separate sets of sheets therein. ¹⁰⁵

In each of the forms heretofore described, a finishing or cover plate 15 is secured outside the backing plate 1, and opposite ends

of this plate 15 flare and are bent upwardly as indicated at 16—16 in Fig. 3 to position the various parts. The side edges are likewise crimped over at 17—17 for the like purpose of securing the parts together.

In the form shown in Fig. 5 there is an outer cover member 18 and rods 21—22 corresponding to binder rings, may pass through the channel members and be secured to each other as by means of a threaded joint. Sheets may thus be permanently secured in the channel, and in the space between the two channels, a book or sheets such as 23, may be detachably held on the rods or binder rings 21—22. The parts may be of any desired proportions and this form is well adapted for holding a book such, for example, as a telephone or city directory.

In the detail shown in Fig. 6, instead of having the holding means in the form of channels, two washers 24—25 may be held on the rod or ring 21'. An outer washer 26 may be provided in order to securely hold and support the backing cover and prevent the head 27 from injuring the soft flexible material. The form shown in Fig. 6 is of course, adapted for use in connection with the form of binder disclosed in Fig. 5.

In the modification shown in Fig. 7, there is an outside flexible back member 28 within which is secured a loose leaf binder member 29 and within which is permanently secured a book 30.

In all of the forms herein shown the permanently bound sheets and the temporarily bound loose leaf sheets are held in the same binder or cover and are separated from each other at the points of support.

The devices of the character herein described are especially adapted for use in situations where it is desired to retain certain sheets or books permanently in a binder and at the same time make it possible in the same binder, to alter, rearrange or change certain sheets to meet varying conditions.

While I have disclosed preferred forms of the invention, I wish it understood that various changes and modifications may be made within the scope of the appended claims.

I claim:

1. In a device of the character described, a unitary binder member, means for permanently securing a plurality of sheets to said unitary binder member, and means for detachably securing a plurality of sheets directly to said unitary binder member, said permanently and detachably secured sheets being separated at the points of securing.

2. In a binder, a supporting back member for permanently holding sheets and for detachably holding sheets, means for permanently securing a plurality of sheets to said back member, means for detachably securing a plurality of sheets directly thereto, and means for separating said permanently attached sheets from the other sheets at the points of support of said sheets.

3. In a binder, a supporting member, means for permanently securing sheets thereto, and means passing through other sheets for detachably securing said other sheets thereto, said means being permanently united.

4. In a binder, a supporting back member, means for permanently securing a plurality of sheets to said back member, and means united to said back member for detachably securing a plurality of sheets thereto, said last mentioned means passing transversely through said detachably secured sheets, whereby the detachably secured sheets may be removed without disturbing said permanently secured sheets.

5. In a binder, a resilient backing plate, a hinge member associated with said backing plate and held in position thereon, means secured to said hinge member for permanently securing sheets thereto, and means for detachably securing sheets thereto.

6. In a binder, a curved resilient backing plate, hinge elements associated with said backing plate, a channel member secured to one of said hinge elements, means for permanently securing sheets within said channel, a binder ring secured to the other hinge element for detachably holding other sheets.

ROLAND WINCHESTER SELLEW.
